METHOD OF SPLICING TWO WEBS IN
OVERLAPPING RELATIONAlfred C. Robertson, Rochester, N. Y., assignor to
Eastman Kodak Company, Rochester, N. Y., a
corporation of New Jersey

Application August 9, 1941, Serial No. 406,159

5 Claims. (Cl. 154—42)

The present invention relates to the method of splicing two webs in overlapping relation, and particularly to the method of splicing two webs of hygroscopic material which will insure a flat splice.

It is common practice to splice the ends of two or more webs of material together so that they can be fed as a continuous strip through a series of coating and drying steps. The webs to be coated are usually brought into the unwinder room of the coating machine in large stock rolls, and as one roll is just about finished another roll is brought in and spliced to the end thereof and this process continues with a continuous web passing through the coating and drying machines constantly, such continuous web being composed of several webs spliced in endwise overlapping relation.

Splicing the webs together has offered a number of difficulties in the past. The major difficulty was the tendency of the splice between two webs to pucker, or buckle, transversely of the web. This buckling not only results in the arc of the web breaking as it passes over the pulleys or rolls of the machine, but streaks in the coating occur where the web is puckered due to the fact that the coating material naturally runs to the bottom of the valleys. The result of this streaking is to increase the amount of coated web which has to be removed in the vicinity of the splices with the result that there is a great amount of coated web which has to be wasted.

Therefore, one object of the present invention is to provide a method of splicing two webs in overlapping relation so that the splice will be flat and remain flat until purposely ruptured.

Another object is to provide a method of forming a flat splice which is commercially practical and can be carried out without necessitating a shut down of the coating and drying machine.

And another object is to provide a method of forming a flat splice which is simple to carry out and requires little or no special apparatus.

The novel features that I consider characteristics of my invention are set forth with particularity in the appended claims. The invention itself, however, both as to the steps necessary thereto, and additional objects and advantages thereof, will best be understood from the following description of specific embodiments when read in connection with the accompanying drawings in which,

Fig. 1 is a partial side elevation of a splicing apparatus shown in my U. S. Patent 2,213,744,

issued Sept. 3, 1940, and showing a suitable piece of apparatus associated therewith for treating one end of a web to be spliced in accordance with the present invention.

5 Fig. 2 is a perspective view of the apparatus in which one end of the web to be spliced is treated in accordance with the present invention.

Fig. 3 is an enlarged sectional view of the apparatus shown in Fig. 2 with an end of a web 10 to be treated shown inserted thereunto, and

Fig. 4 is a graph depicting how the dimensions of a web varies with the length of time during which it is dried in accordance with one embodiment of the present invention.

15 Like reference characters refer to corresponding parts throughout the drawing.

As set forth above, it has been found that when two webs of material are spliced in overlapping relation prior to being fed through a coating and drying machine as a continuous strip 20 that the splice buckled transversely of the web causing the splice to rupture at the arches of the web in the machine and causing the coating to become streaked in the vicinity of the splice.

25 After an exhaustive study of this condition, I found that this buckling of the splice is due primarily to the fact that the outer wrap of web on a fresh stock roll is in equilibrium with a different relative humidity from that prevailing in 30 the region of the inner wrap on the previous stock roll to which it is to be spliced. This reasoning has been substantiated by direct measurements which were made of the outer wrap of a fresh stock roll and the inner wrap of a previous

35 stock roll. The theory that buckling of the splice is due to humidity difference has been proved by a number of experiments where a web of material was cut, and spliced to itself and coated under ordinary conditions. The results of these

40 tests indicated strongly that when two pieces of a web were in equilibrium with the same relative humidity that the splices were very flat, buckling was absent, and streaking due to buckling of the splice was negligible.

45 It might be pointed out that this buckling of a splice of two webs is prevalent only when the webs are of hygroscopic material. A web of hygroscopic material will alter in dimensions as the 50 relative humidity of the air about it changes. Paper, cloth, cellulose derivative film base, etc. are examples of webs which are hygroscopic and will alter in dimensions with changes in the relative humidity of air surrounding them. While narrow webs of hygroscopic material will show

no appreciable change in width due to changes in relative humidity, with webs 40 inches wide, which are common in coating procedures, changes in width of the web due to different relative humidity conditions encountered have been found to range between .010 inch and .040 inch. The difference is generally in the neighborhood of .030 inch and is easily perceptible by the use of a steel scale.

It will, therefore, be clearly understood that if a web in equilibrium with an atmosphere having one relative humidity is spliced in overlapping relation with a web in equilibrium with an atmosphere having a different relative humidity and the two are passed through an atmosphere having a relative humidity the same as one of said atmospheres or different from both thereof, the two webs will vary in width by different amounts with the result that there will be a buckling of the splice between the two. This I have found is the cause of the buckling of the splice between two webs in the above referred to coating and drying process.

A web when it is fabricated and rolled up into a stock roll generally is in equilibrium with a very low relative humidity. If the stock roll is stored in a storage room or moved into the unwinding room of the coating machine where the relative humidity is higher than that with which the web material is in equilibrium it has been found that the outer wraps of the roll will in a short time swell, or increase in moisture content, until it is in equilibrium with the relative humidity of the storage, or underwinder, room of the coating machine. It has been found, however, that no matter how long a stock roll of the web is kept in the storage room, or in the unwinder room, the inner wraps of the roll will never come into equilibrium with the relative humidity of said room. This is probably due to the fact that the inner wraps of the stock roll are usually covered at the ends with metal plates and are so tightly rolled that the air of the room can reach the center of them only by diffusion from the edges of the roll. Consequently, since the outer wraps of a new stock roll will always be in equilibrium with a relative humidity different from the inner wraps of a previous, or unwinding, stock roll, the two will tend to vary differently in width with changes in relative humidity after they are spliced together in this condition. This difference in dimensional change in the two webs will cause the splice between the two to buckle transversely of the web.

As a specific example, suppose a web of material when fabricated has an effective relative humidity, or is in equilibrium with a relative humidity, of 30 per cent. If this stock roll is then moved into the unwinder room of the coating machine the relative humidity of which is 50 per cent, in a short time, e. g. one-half hour, the outer wraps of the roll will have come into equilibrium with this 50 per cent relative humidity but the inner wraps will stay at 30 per cent effective relative humidity, or thereabouts, regardless of the time the roll remains in this room. Now if another stock roll is moved into the unwinder room it will be appreciated that the outer wrap thereof which is in equilibrium with a 50 per cent relative humidity must be spliced to the inner wrap of the previous roll which is in equilibrium with a relative humidity of 30 per cent. The result will be that when the spliced webs are then moved through the coating and drying stages in which the relative humidity may be the same as

that in the unwinder room, or different therefrom, the two webs will vary by different amounts in width so that the splice will buckle.

I have found that this buckling of the splice between two webs of hygroscopic material can be effectively overcome if the two webs are brought into equilibrium with the same relative humidity immediately prior to the splicing operation. This technique can be carried out in a number of different ways, namely, by subjecting the two webs to an atmosphere having the same relative humidity until they are in equilibrium therewith, or one web may be subjected to an atmosphere having a relative humidity with which the other web is in equilibrium with.

However, I have developed a technique whereby the process of bringing the two webs into equilibrium with the same relative humidity can be done in a routine manner in the unwinder room of the coating machine without necessitating an alteration in the speed of the splicing or coating and drying operations in any way. According to my technique, the end of the web on the outside of the new stock roll is dried or brought into equilibrium with the same relative humidity with which the inner end of the previous stock roll is in equilibrium, or the end of the outside lap on the new stock roll is dried until its effective relative humidity is 30 per cent instead of 50 per cent, using the figures of the above noted example.

In the graph constituting Fig. 4 of the drawing, the solid line shows how the width of the web being dried varies with the length of time during which it is being dried. The dot-dash line of the graph shows the desired width, or the width of the web on the inner wrap of the previous stock roll having an effective relative humidity which is to be obtained. It will be appreciated that the width of a hygroscopic web will vary directly as the change in relative humidity with which it is in equilibrium so that instead of change in width the ordinate of the graph could be marked in relative humidity. The end of the outer wrap of the new stock roll could be dried just to the point where it was the desired width, or the width of the inner wrap of the previous stock roll, but I have found that since a web will more readily increase in moisture content when exposed to an atmosphere having a higher relative humidity than the one with which it is in equilibrium, then it will give up moisture, and a more accurate control is obtained by drying the end of the web below the desired value and allowing it to pick up moisture from the atmosphere of the unwinder room. The dotted lines of the graph indicate the rate at which the web will pick up moisture to reach the desired width, or effective relative humidity.

In actual practice, this drying of the end of the web on the new stock roll can be effectively carried out by the apparatus shown in Fig. 1. The splicing apparatus, proper, as indicated, may be of the form best shown in my U. S. Patent 2,213,744, issued September 3, 1940, which is particularly adapted for splicing relatively wide webs of material in overlapping endwise relation. The splicing apparatus per se forms no part of the present invention but is only shown to indicate how the apparatus for treating the end of one web which is to be spliced to a second web may be associated with the splicing member thereof to carry out the treating step in a routine manner without necessitating a slowing down of the feeding of the continuous web.

Broadly, the splicing apparatus comprises a support 1 on the top 2 of which the ends of two webs W and W' to be spliced are adapted to be placed in overlapping endwise relation below the pressure element 10 of the apparatus. Above the surface of the support 1 of the splicing apparatus there is disposed in any suitable manner, as by brackets 5, a chamber 6 which is of a general tubular shape and having two spaced radially extending lips 7 forming a slot into which the end of the web of hygroscopic material W to be dried is adapted to be inserted as shown. The chamber 6 is closed at both ends and is preferably equal in length to the width of the web W. Dry air held at the same temperature as that of the web which is being unwound is forced into the chamber 6 through a conduit 8 communicating therewith, and may be distributed over the length of the chamber by any suitable form of baffles desired, or may be directed against the end of the web to be distributed by the force of impingement of the blast against the web, see Fig. 3. The end of the web W is left in the chamber 6 until it has been shrunk to a point below the desired width, see Fig. 4, after which it is withdrawn into the atmosphere of the unwinder room in which the splicing apparatus is preferably located and allowed to increase to the desired width, or to the width of the end of the web W' to which it is to be spliced. The air for drying the web may be dried in any number of different ways. For example, compressed air which has been passed through a U-tube packed with dry ice may be forced into conduit 8; or my experience has shown that 75 pounds of compressed air which has been chilled to 40° F. is dry enough if the water is removed at the higher pressure and then the air is allowed to expand to atmospheric pressure. Inasmuch as only the ends of the two webs are in overlapping relation when spliced together, only that portion of the web W on the new stock roll which is to overlap the end of the other web W' need be in equilibrium with the same relative humidity as said other web. Consequently, the chamber 6 need only be sufficiently large to dry the end of the web on a new stock roll as indicated in Fig. 3. After the end of the web W has come into equilibrium with the same relative humidity as the end of the web W' they may be brought into overlapping relation under the pressure element 10 of the splicing apparatus and be spliced in the manner set forth in my above noted patent.

It will be readily appreciated from the above description that I have provided a novel method of splicing the ends of two hygroscopic webs in overlapping relation so that a splice will be obtained which will remain flat regardless of what changes in relative humidity the spliced webs are subjected after being spliced. The technique disclosed is particularly adapted for being carried out in a routine manner in the unwinder room of a coating machine, or other type of machine, adapted to perform one or more operations on a continuous web without necessitating a shut down, or a slowing up, of the operations normal to such machines. The free end of the new stock roll is readily accessible and can be dried in the manner set forth during the time the last few wraps of the previous stock roll are being wound off. Then when the inner end of the previous stock roll is available, the free end of the new stock roll is properly conditioned and ready to be spliced thereto in a manner set forth

in my U. S. Patent 2,213,744, issued September 3, 1940, thus requiring no shut down of the machine. This novel method of splicing not only cuts down the amount of coated web heretofore wasted due to streaking of the coating in the vicinity of the splice because of transverse buckling thereof, but eliminates ruptures of splices due to buckling which cause a shut down of the coating and drying machines and necessitate a rethreading thereof.

Although I have shown and described one specific embodiment of my invention, I am fully aware that many modifications of the same are possible. My invention, therefore, is not to be restricted except in so far as is necessitated by the spirit of the appended claims.

Having thus described my invention, what I claim is new and desire to secure by Letters Patent of the United States is:

- 20 1. In the method of splicing two webs of the same hygroscopic material in overlapping relation, the steps of bringing the two portions of said webs which are to be overlapped into equilibrium with separate atmospheres having the same relative humidity, and splicing said webs together while said portions are in such condition.
- 25 2. In the method of splicing two webs of hygroscopic material in overlapping relation, one of which webs is in equilibrium with an atmosphere having a given relative humidity and the other of which is in equilibrium with a second atmosphere having a higher relative humidity than the first mentioned atmosphere, the steps of subjecting said second mentioned web to the drying action of an atmosphere the relative humidity of which is below that of said first mentioned atmosphere, then subjecting said web to said first mentioned atmosphere, until it is in equilibrium therewith, then splicing the two webs together.
- 30 3. In the method of splicing two webs of hygroscopic material having different moisture contents together in overlapping relation, the steps of drying that portion of the web having the greatest moisture content which is adapted to be in overlapping relation with the other with a blast of drying air until the moisture content thereof is slightly less than the moisture content of the other web, subjecting said dried portion of the treated web to the atmosphere surrounding the other web until the same is in equilibrium with said atmosphere and the moisture content thereof is the same as the moisture content of the other web, and splicing the two webs together while they are in equilibrium with the same atmosphere.
- 35 4. In the method of splicing two webs of hygroscopic material in overlapping endwise relation and the ends of which webs that are to be spliced together are in equilibrium with atmospheres of different relative humidities, the steps of drying the end of the web which is in equilibrium with the atmosphere of higher relative humidity until it is in equilibrium with an atmosphere the relative humidity of which is lower than that which the second web is in equilibrium with, then subjecting the end of said web to the atmosphere with which the second web is in equilibrium with until it is also in equilibrium with said last mentioned atmosphere, and splicing the two ends while they are in equilibrium with the same atmosphere.
- 40 5. In the method of splicing two webs of the same hygroscopic material in overlapping relation, one of which webs is in equilibrium with an atmosphere having a given relative humidity and
- 45
- 50
- 55
- 60
- 65
- 70
- 75

the other of which is in equilibrium with a second atmosphere having a higher relative humidity than the first-mentioned atmosphere, the steps of drying said second-mentioned web until it is in equilibrium with the same relative humidity as

said first-mentioned web, said drying step being carried out at a rate greater than that which

would naturally occur by subjecting the second-mentioned web to the atmosphere which the first-mentioned web is in equilibrium with, and splicing said webs in overlapping relation when in such condition.

ALFRED C. ROBERTSON.
